United States Patent Office.

GERARD SICKELS, OF BOSTON, MASSACHUSETTS.

Letters Patent No. 77,542, dated May 5, 1868.

IMPROVEMENT IN WATER-METERS.

The Schedule referred to in these Letters Patent and making part of the same.

Be it known that I, GERARD SICKELS, of Boston, in the county of Suffolk, and State of Massachusetts, have invented a new and useful Improvement in Water-Meters, of which the following is a full, clear, and exact description, reference being had to the accompanying drawings, making a part of this specification, in which—

Figure 1 represents a longitudinal vertical section of a water-meter embodying my improvements.

Figure 2 is a transverse vertical section of the same; and

Figure 3 is partly a plan view and partly a horizontal longitudinal section.

Figure 4 is a modification of the device for operating the slide-valve piston.

Similar letters indicate like parts in the several figures.

The object of my invention is to produce a simple, cheap, and accurate apparatus for measuring a supply of water; and the invention consists in effecting the entire motion of the valve by shifting the bearing of the foot of a prop attached to the under side of the valve-piston, so that as the foot of the said prop is moved towards the centre of its track, the piston is elevated, and after the said foot passes the centre, the pressure of the water upon the piston will force the foot of the prop to the opposite end of its track, thus inclining it in the opposite direction, and causing the upper end of the prop to push the valve in the opposite direction. The prop of the valve-piston extends down into the cylinder, so that it can be operated upon by the direct action of the cylinder-piston.

Referring to the drawings, *a* represents a cylindrical casing, provided with heads, *b b*, at either end. Within the said cylinder are two pistons, *e e*, connected to each other by a bar, *d*, provided with a slot at its central portion, through which projects the lower end of the prop *o*. *g* is the induction-chamber, over which is fitted the cap *f*, attached to the upper portion of the cylinder *a*. *h* is the inlet-opening to the induction-chamber *g*, and *i* is the outlet at the centre of the side of the cylinder *a*, as shown in fig. 2. *m* is a slide-valve fitted on a seat, *e*, forming a part of the cylinder. It is surmounted by a valve-cylinder, *l*, in which is fitted a piston, *k*. *n n'* are the ports cast in the cylinder. To the under side of the valve-piston *k* is hinged or pivoted a prop, *o*, consisting of a metal bar, extending downwards through the slot *r*, in the connecting-bar *d* of the cylinder-pistons. At a point somewhat above the connecting-bar *d*, it is provided with rollers *p p* on either side, which have their bearings in corresponding seats, *q q*. The said seats curve upwardly at their ends, as seen in fig. 1, so as to arrest the progress of the rollers *p p* of the prop *o*, at the limit of the motion of the latter in each direction. *s s* are uprights which support the seats *q q* of the rollers *p p*.

The prop *o*, instead of being supported by rollers upon the seats *q q*, may be pivoted to an auxiliary prop, *o'*, which is hinged or pivoted to a proper supporting piece attached to the centre of the lower inner surface of the cylinder *a*, as shown in fig. 4; the upper end of the said auxiliary prop *o'*, resting at each alternate throw of the cylinder-piston against the opposite sides of the opening in the upper portion of the cylinder *a*, so as to cause the prop *o* to shift its point of bearing to incline in opposite directions, and only move the valve after reaching the bearing-points.

An indicating-device for determining the quantity of water passing through the meter, may be arranged in any suitable manner on the top of the cap *f*, so as to be operated by the vertical motion of the valve-piston.

The operation is as follows: The water being introduced into the induction-chamber *g*, through the inlet-opening *h*, will, by its pressure, force the valve *m* upon its seat, and also the piston downwards; at the same time passing downwards through the ports alternately at either side, will operate the cylinder-piston *e e* in the usual manner; and, passing to the centre of the cylinder, between the pistons, will be ejected through the outlet *i*, as indicated by the arrows. During the motion of the piston, the prop *o*, extending down through the opening *r* in the connection-bar *d*, is moved along until the foot of the prop has passed the perpendicular centre, elevating the valve-piston while assuming the perpendicular, when the pressure upon the valve-piston will cause the foot of the prop to travel in a direction to the opposite bearing. When the prop has changed its inclination in an opposite direction, its upper end will be forced forward and downward, thus imparting the proper motion to the valve to change the ports.

What I claim as my invention, and desire to secure by Letters Patent, is—

1. Effecting the entire motion of the valve by shifting the bearings of the foot of the prop *o*, attached to the under side of the valve-piston, substantially as set forth.
2. Extending the prop of the valve-piston down into the cylinder, so that it can be operated upon by the direct motion of the cylinder-piston.
3. The combination of the valve-piston *k*, the movable prop *o*, and the connecting-bar *d*, substantially as and for the purpose described.

In testimony whereof, I have signed my name to this specification in the presence of two subscribing witnesses.

GERARD SICKELS.
